UNITED STATES PATENT OFFICE.

FRANCIS ERWIN BORKENHAGEN, OF CALDWELL, IDAHO.

FLYING-MACHINE.

1,008,887.

Specification of Letters Patent. Patented Nov. 14, 1911.

Application filed March 18, 1911. Serial No. 615,295.

To all whom it may concern:

Be it known that I, FRANCIS E. BORKENHAGEN, a citizen of the United States, residing at Caldwell, in the county of Canyon 5 and State of Idaho, have invented certain new and useful Improvements in Flying-Machines; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to new and useful improvements in biplanes and comprises an apparatus having various details of construction and combinations and arrangements of parts which will be hereinafter 20 fully described and then specifically defined in the appended claims.

I illustrate my invention in the accompanying drawings, in which:—

25 Figure 1 is a top plan view of my invention. Fig. 2 is an end elevation. Fig. 3 is a perspective view of the apparatus, and Fig. 4 is a detail perspective of a part of the invention.

30 Reference now being had to the details of the drawings by letter, A designates a motor, the shaft A' of which has fixed thereto a beveled gear A⁵ which is in mesh with a beveled gear B' which is loosely mounted 35 upon a shaft B which is loosely journaled in the standards H of the frame. A sprocket wheel A² is fixed to rotate with the gear wheel B' which is loosely journaled in the standards H of the frame. A sprocket 40 chain C passes about the sprocket wheel A² and a similar sprocket wheel A⁶ which is fixed to the driving shaft A⁹ journaled in the upper portions of the standards H. Said shaft A⁹ has fixed thereto a beveled 45 gear D which is in mesh with a beveled gear O² fastened to the shaft O which is journaled in a suitable bearing O³ upon the cross-piece O⁴ connecting the two planes F, F. A propeller having arms O' is fixed 50 to the shaft O and has blades O⁵ thereon disposed at inclinations to one another.

Fastened to the shaft B are the pulleys I², and I' designate belts, each passing about a pulley I² and about a pulley I which is 55 fastened to a cross-piece I³ connecting the two planes F. It will be noted that each

of the planes F is recessed away as at F' to allow the planes to swing freely without interference from the sprocket chain C or the cross-piece C².

60

A shaft L⁴ is journaled in an aperture in the standard A⁶ and also in the yoke A⁷ and has a beveled gear L' at its forward end which is in mesh with a beveled gear L⁶ fixed to the shaft B. A pulley L² is fixed 65 to the shaft L⁴ and a rope L⁷ passes about said pulley and also about a pulley L⁸ which is fixed to the crank shaft L⁵, forming a means whereby the operator, by turning the crank, may cause the shaft L⁴ to rotate and 70 also the aeroplanes to swing from horizontal to a vertical position or vice versa.

75 Seats N are mounted upon the movable platform N^x and a cable or rope N' is fastened to one end of the platform and passes about a pulley N⁶, thence about a pulley N⁷ which is fixed to the shaft B. Said cable or rope, after passing about the pulley N⁷, passes forward about a pulley N¹⁰, shown clearly in Fig. 4 of the drawings, thence 80 passes rearward and about a pulley N⁸ and is fastened to the rear edge of the seat. By this mechanism, it will be noted that the operator by turning the crank L⁵ may cause the biplanes to swing from horizontal to 85 vertical positions and vice versa and at the same time, in the event of the biplanes being turned in vertical positions, to cause the platform carrying the seat to be drawn toward the biplanes or, when the shaft L⁴ is 90 turned in the reverse direction, to cause the platform to be moved farther from the biplanes when the latter are horizontally disposed, thus forming a means for changing the center of gravity which, to balance the 95 apparatus, should be as near as possible underneath the biplanes when the latter are vertically disposed but, when in the position shown in Fig. 3, may be farther therefrom.

100

A rudder Q has pintles Q' mounted in suitable bearings in the frame of the apparatus and is provided with cords or chains Q⁶ which pass over the pulleys Q⁸, thence over the pulley Q⁹ fastened to the rotatable shaft Q¹¹ which is journaled at its forward end in the yoke A⁷ and its rear end in the frame of the apparatus. A pulley Q¹² is fastened to the shaft Q¹¹ and a cable Q¹³ 105 passes about said pulley and also a pulley M' mounted upon the crank shaft M and forming means whereby the operator, by 110

turning the crank M, may cause the rudder to swing in one direction or the other.

The operation of my invention will be readily understood and is as follows:—

- 5 When it is desired to cause the apparatus to be elevated, the aeroplanes may be swung to vertical positions by the operator turning the crank L⁵, causing the shaft L⁴ to rotate and also the shaft B which is geared thereto.
- 10 The shaft B being put in rotation will impart a rotary movement to the pulleys I which are fastened to the cross-pieces I³ connecting the biplanes, thus throwing the same to vertical positions. As the shaft B rotates, the platform will be drawn toward the biplanes to get the center of gravity as near as possible thereto, the drawing forward of the platform being made possible by the cable N' which is fastened to the 15 seat and passes about the pulleys as shown clearly in Fig. 4 of the drawings.
- 20

What I claim to be new is:—

1. An automatic lifting and balancing bi-plane comprising a frame having standards, 25 an upper and a lower horizontally disposed shaft mounted in suitable bearings in said standard, aeroplanes, cross-pieces connecting said planes and holding the same in parallel relation and fastened to the upper of 30 said shafts, a gear wheel fixed to said upper shaft, a propeller shaft mounted in a suitable bearing in one of said cross-pieces and driven by said gear wheel, a pulley upon the lower of said shafts, a pulley fixed to 35 one of the cross-pieces, a belt about said pulleys, a beveled gear wheel upon said lower shaft, a horizontally disposed rotatable shaft mounted in suitable bearings in the frame independent of the standards, a bevelled pinion thereon meshing with the bevelled gear upon said lower shaft, a pulley mounted in said horizontally disposed shaft, a crank shaft and belted connections between the latter and pulley upon the horizontally 40 disposed shaft, a movable platform upon the frame, a cable fastened at the opposite ends of said platform, pulleys about which the cable passes, one of which pulleys is fixed 45 vertically disposed shaft.

2. An automatic lifting and balancing bi-plane comprising a frame having standards, an upper and a lower horizontally disposed shaft mounted in suitable bearings in said 50 standard, aeroplanes, cross-pieces connecting said planes and holding the same in parallel relation and fastened to the upper of said shafts, a gear wheel fixed to said upper shaft, a propeller shaft mounted in suitable 55 bearings in one of said cross-pieces and

driven by said gear wheel, a pulley upon the lower of said shafts, a pulley fixed to one of the cross-pieces, a belt about said pulleys, a beveled gear wheel upon said lower shaft, a horizontally disposed rotatable shaft mounted in suitable bearings in the frame independent of the standards, a bevelled pinion thereon meshing with the bevelled gear upon said lower shaft, a pulley mounted in said horizontally disposed shaft, a crank shaft and belted connections between the latter and pulley upon the horizontally 60 disposed shaft, a movable platform upon the frame, a cable fastened at the opposite ends of said platform, pulleys about which the cable passes, one of which pulleys is fixed to said lower shaft and the other journaled upon the frame.

3. An automatic lifting and balancing bi-plane comprising a frame having standards, 75 an upper and a lower horizontally disposed shaft mounted in suitable bearings in said standard, aeroplanes, cross-pieces connecting said planes and holding the same in parallel relation and fastened to the upper of 80 said shafts, a gear wheel fixed to said upper shaft, a propeller shaft mounted in a suitable bearing in one of said cross-pieces and driven by said gear wheel, a pulley upon the lower of said shafts, a pulley fixed to 85 one of the cross-pieces, a belt about said pulleys, a beveled gear wheel upon said lower shaft, a horizontally disposed rotatable shaft mounted in suitable bearings in the frame independent of the standards, a bevelled pinion thereon meshing with the bevelled gear upon said lower shaft, a pulley mounted in said horizontally disposed shaft, a crank shaft and belted connections between 90 the latter and pulley upon the horizontally 95 disposed shaft, a movable platform upon the frame, a cable fastened at the opposite ends of said platform, pulleys about which the cable passes, one of which pulleys is fixed to said lower shaft and the other journaled 100 upon the frame, a rudder, a rope fastened thereto, a pulley about which the rope winds, and a crank shaft for turning the pulley about which the rope passes.

In testimony whereof I hereunto affix my 105 signature in the presence of two witnesses.

FRANCIS ERWIN BORKENHAGEN.
